UNITED STATES PATENT OFFICE

2,314,240

CONTROL DEVICE

Joseph W. Owens, Schenectady, N. Y., assignor to
 General Electric Company, a corporation of
 New York

Application December 31, 1941, Serial No. 425,153

6 Claims. (Cl. 200—83)

My invention relates to control devices, more particularly to electric refrigerator motor control devices, and has for its object a simple and reliable control device provided with a single knob for adjusting the device for a desired refrigerator temperature and for adjusting the device for a defrosting cycle of relatively wide temperature range.

This invention is an improvement over the invention described and claimed in a copending application Serial No. 400,632, filed on July 1, 1941 by Edgar H. Ayers, assigned to the same assignee as this invention.

In carrying out my invention in one form I provide an adjustable stop for the switch arm in its open circuit position together with a projection on the knob for adjusting the bellows spring, which projection engages the stop when the knob is moved to a predetermined position thereby to move the stop farther out of the path of the switch arm. This provides for an increased opening movement of the switch arm whereby a high defrosting temperature in the evaporator is required to reclose the switch arm. I also provide a second projection on the knob for engaging the switch arm to hold the switch arm in its open circuit position when the knob is turned to another position.

For a more complete understanding of my invention, reference should be had to the accompanying drawing in which Fig. 1 is a plan view of a control device embodying my invention; Fig. 2 is a sectional view along the line 2—2 of Fig. 1 looking in the direction of the arrows; Fig. 3 is a bottom view of the device with the knob removed; while Fig. 4 is a view of the inner operative end of the knob.

Referring to the drawing, in one form of my invention I provide over-center spring snap operating means for the switching means comprising a switch arm 10 mounted on a pivot 11 and provided with a flexible arm 12 carrying on its end a movable contact 13 which cooperates with a stationary electric contact 14. This switch arm is actuated by an operating arm 15 having a pivot 16 and operated by a bellows temperature responsive device 17. The over-center spring connection between these two arms 10 and 15 comprises a U-shaped link 18 having its ends pivotally secured on a pivot 20 on the ends of two laterally extending projections 19 (only one of which is shown) which are spaced apart and secured to the end of the operating arm 15. The cross or base portion of the link is connected by an over-center helical tension spring 22 with a projection 22a on

the end of the switch arm 10 and extending laterally therefrom. This projection 22a is positioned to move between the projections 19 upon relative movement between the two arms 10 and 15. Stops 24 and 25 made of electrically insulating material are provided on opposite sides of the link 18 adjacent its closed movable end for the purpose of limiting the movement of this end.

In the operation of this over-center snap mechanism, the determining factor is the relative positions of the pivot 20 and the pivot 23 forming the connection between the spring 22 and the projection 22a. When the pivot 20 is below the pivot 23, as viewed in Fig. 1, the spring applies a force holding the link 18 against the upper stop 24 and a force to the arm 10 biasing it in a counterclockwise direction so as to hold the contact 13 in engagement with the contact 14. If now the arm 15 is raised, as viewed in Fig. 1, until the pivot 20 is slightly above the pivot 23, then the spring applies a component of force tending to move the link 18 clockwise about its pivot 20 into engagement with the lower stop 25. This, of course, changes the position of the end of the spring and thereby reverses its component applied to the arm 10. As seen in Fig. 1, the spring applies a force along a line passing through the pivot 23 and extending above the pivot 11. Soon after the link 18 begins to move downward the line of force of the spring moves below the pivot 11 whereby a counterclockwise torque is applied to the arm 10 and the arm is therefore snapped in a counterclockwise direction to its open circuit position.

In accordance with my invention, I provide for an abnormally great movement of the arm 10 in the circuit opening direction whereby the pivot 23 is allowed to move to a lower position, as seen in Fig. 1, and as a result, in order to move the contact arm 10 to its closed circuit position, the arm 15 must be moved correspondingly lower. To effect this a higher bellows pressure and higher temperature are required with the result that the evaporator of the refrigerator to the temperature of which the bellows is responsive is allowed to reach a high defrosting temperature before the refrigerator motor is restarted.

In the form of my invention shown, I provide an extension 26 extending downwardly and laterally from the switch arm 10, as viewed in Fig. 1. On its end this extension 26 is provided with a portion 26a behind the bellows spring adjusting screw 27, parallel therewith, and projecting through an aperture 28 provided for it in the 55 enclosing casing 29 for the mechanism into co-

operative relation with a knob 30 secured on the end of the adjustment screw 27.

As shown in Fig. 3, a stop 31 is provided on the base of the casing for limiting the movement of the end 26a toward the right hand, i. e., in the opening direction. This stop, as shown, is the laterally bent end of a wire 32 lying in a recess 33 in the bottom of the electrically insulating casing 29. The other end of this wire is secured to the casing by means of the clamping screw 34. A bend 35 in the wire engages the wall of the recess 33 thereby to position the wire.

Also, the wire is provided with a laterally extending bent portion 36 extending downward, as seen in Fig. 1, which portion is in position to be engaged by a cam projection 37 on the inner end of the knob 30. Thus movement of the knob in a counterclockwise direction, looking at the bottom of Fig. 1, brings the curved portion 37a of the cam into engagement with the projection 36 whereby this projection is pushed out toward the right hand and the stop 31 carried by the wire likewise moved toward the right hand out of the path of the extension 26a to the position shown in dotted lines in Fig. 3. It will be understood that the wire 32 is made of spring material and bends to provide for this displacement of the stop 31.

Also provided on the inner end of the knob is a projection 38 which is in position to engage the extension 26a and move it also toward the right hand by a still greater counterclockwise movement of the knob 30. Thus the extension 26a is relatively close to the adjustment screw 27 while the projection 36 is a greater distance away from the screw 27. Likewise, the projection 38 is the same distance from the center line of the knob as the extension 26a and the cam 37 is a greater distance away from the center line of the knob and moves outside of the extension 26a and does not engage it. Likewise, the projection 28 upon maximum clockwise rotation of the knob moves inside of the projection 36 and does not engage it.

Moreover, the cam 37 is long enough in the direction of rotary movement of the handle so that it still engages the projection 38 when the knob is turned its maximum amount against the extension 26a. In other words, for the defrost setting, the knob is turned to a position in which the middle of the cam 37 engages the projection 36 so that the stop 31 is moved to the dotted line position (Fig. 3) but the projection 38 is to the left of the extension 26a, as viewed in Fig. 3, and does not interfere with the extension. Thus the switch arm is free to move to its normal closed position. This position of the knob for the defrost setting will be indicated by a suitable mark (not shown) on the knob cooperating with a mark on the casing.

Not only must the bellows 17 compress the spring 39 farther when the knob has been turned to this defrost setting which would require an increased bellows pressure and temperature, but the operating arm 15 engages a spring pressed plunger 40 which is pressed upward by the spring 41 normally until the flange 42 on the plunger engages the lateral end of a bracket 43. It will be understood that under normal operating conditions with the stop 31 in its normal position, the bellows arm 15 is not depressed far enough to engage the plunger 41 in order to move the contact arm 10 to its closed circuit position. When the bellows arm engages the plunger 40, the spring 41 still further loads it and increases the

required bellows pressure and temperature to the desired high defrosting value.

It will be understood that the adjustment screw 27 is provided with a coarse thread having sufficient pitch to give the desired range of adjustment of the bellows spring 39 in somewhat less than one complete revolution of the screw. The lower end of the spring 39 rests on a traveling nut 44 in threaded engagement with the screw. This nut is prevented from turning by means of a pair of prongs 45 (only one of which is shown) embracing a rib on the inner wall of the casing, which rib extends parallel with the screw. Moreover, the pitch of the screw threads is preferably in such direction that counterclockwise movement of the knob compresses the spring 39 so that when the defrost setting is made the spring is compressed.

A suitable connection terminal 46 is provided for the stationary contact 14, the two being connected together by a suitable screw or rivet. Also, a connection screw 47 spaced and electrically insulated from the screw 46 is provided for the movable contact 13. This terminal 47 is connected to a rigid conductor 48 inside the casing which, in turn, is electrically connected by means of a flexible lead 49 to the contact arm 10.

As previously stated, the bellows 17 preferably is responsive to the temperature on the evaporator of the refrigerator, the end 50 of the closed tube connected with the bellows being suitably clamped on the evaporator so as to be responsive to the temperature of the evaporator. As shown, this end 50 is provided in lieu of a bulb with a twisted portion formed by bending a portion on the end of the tube back on the tube and then twisting together the two lengths thus formed, as shown in the drawing.

A stop 51 is provided on the knob on its periphery in position to engage a stop 52 on the bottom of the casing thereby to limit the freedom of rotation of the knob to slightly less than one complete revolution, i. e., to one revolution less than the combined circumferential lengths of the stops.

Preferably, the projections 37 and 38 on the handle perform their control functions near or at the limits of counterclockwise rotation of the knob as determined by the stops 51 and 52. When the knob is turned to hold the switch arm 10 in its open circuit position, i. e., refrigerator off position, the knob is turned its maximum amount in a counterclockwise direction looking at the bottom of Fig. 1 until the stop 51 engages the stop 52. This brings the stop 38 into engagement with the projection 26a on the switch arm and moves the switch arm to its open circuit position or holds the switch arm in its open circuit position when it happens to be in that position.

A stop 53 on the arm 15 engages with an abutment 54 on the casing to limit the downward movement of the arm 15.

While I have shown a particular embodiment of my invention, it will be understood, of course, that I do not wish to be limited thereto, since many modifications may be made and I therefore contemplate by the appended claims to cover any such modifications as fall within the true spirit and scope of my invention.

What I claim as new and desire to secure by Letters Patent of the United States is:

1. A control device comprising a switch member, a temperature responsive operating member, a spring forming an operating connection between said members for biasing said switch mem-

ber from an open to a closed circuit position upon movement of said operating member in response to an increase in temperature, a stop member for limiting the open circuit position of said switch member to a predetermined normal position, a knob, a projection on said knob for moving said stop member to an abnormal position upon rotation of said knob to a predetermined position thereby to provide for an increased opening movement of said switch member whereby an increased movement of said operating member is required to move said switch member to a closed circuit position, resilient means in the path of movement of said operating member in moving said switch member to a closed circuit position normally not engaged by said operating member when said switch member is in said predetermined normal open position but engaged by said operating member during its said increased movement thereby to increase the required pressure by said operating member for operation of said switch member to its closed circuit position, and a second projection on said knob for engaging said switch member upon rotation of said knob to another predetermined position, thereby to hold said switch member in its open circuit position.

2. A control device comprising a switch member, a temperature responsive operating member, a spring forming an operating connection between said members for biasing said switch member from an open to a closed circuit position upon movement of said operating member in response to an increase in temperature, a stop member for limiting the open circuit position of said switch member to a predetermined normal position, a second spring opposing movement of said operating member, a knob connected to vary the force applied by said second spring upon rotation of said knob, a projection on said knob for engaging said stop member thereby to move said stop member to an abnormal position upon rotation of said knob in a predetermined direction to a predetermined position thereby to provide for an increased opening movement of said switch member whereby an increased movement of said operating member is required to move said switch member to a closed circuit position, resilient means in the path of movement of said operating member in moving said switch member to a closed circuit position normally not engaged by said operating member when said switch member is in said predetermined normal open position but engaged by said operating member during its said increased movement thereby to increase the required pressure by said operating member for operation of said switch member to its closed circuit position, and a second projection on said knob for engaging and moving said switch member to a predetermined position upon rotation of said knob to another predetermined position.

3. A control device for electrically operated refrigerators comprising a switch member, an operating member for said switch member, means responsive to the temperature of the evaporator of a refrigerator for operating said member, a snapping spring connection between said switch member and said operating member, a stop member for limiting the open circuit position of said switch member to a predetermined normal position, a rotatably mounted knob, a projection on said knob for moving said stop member to an abnormal position upon rotation of said knob to provide for an increased opening movement of said switch member and an increased movement

5 of said operating member to move said switch member to a closed circuit position, and a spring pressed member positioned outside the normal range of movement of said operating member in moving said switch member from its predetermined normal open circuit position to its closed circuit position but engaged by said operating member during said increased movement for increasing the required pressure by said operating member for operation of said switch member to its closed circuit position, the temperature of the evaporator for such movement of said switch member to a closed circuit position being increased to a temperature effecting defrosting of the evaporator and said switch member being free to be moved between its closed and open circuit positions by said temperature responsive means in response to the normal low evaporator temperature and said abnormal high defrosting temperature to effect defrosting of the evaporator at said high temperature.

10 4. A control device comprising a switch member, a temperature responsive operating member, a spring forming an operating connection between said members for causing said switch member to snap from an open to a closed circuit position upon movement of said operating member in response to an increase in temperature, a stop member for limiting the open circuit position of said switch member to a predetermined normal position, a spring opposing movement of said operating member in response to an increase in temperature, a knob connected to vary the force applied by said spring upon rotation of said knob, a cam projection on said knob for moving said stop member to an abnormal position upon rotation of said knob to a predetermined position of increased force applied by said spring to provide for an increased opening movement of said switch member whereby an increased movement of said operating member is required to move said switch member to a closed circuit position, a spring pressed member engaged by said operating member during said increased movement, and a second projection on said knob for engaging said switch member to hold it in said open circuit position upon continued rotation of said knob past said predetermined position, said cam being arranged to hold said stop in said abnormal position during said continued movement.

15 5. A control device for electrically operated refrigerators comprising a switch member, an operating member for said switch member, means responsive to normal high and normal low temperatures of the evaporator of a refrigerator for operating said member between closed and open circuit positions, a snapping spring connection between said switch member and said operating member, a stop member for limiting the open circuit position of said switch member to a predetermined normal position, a rotatably mounted knob, a cam on said knob for moving said stop member to an abnormal position upon rotation of said knob to a predetermined position thereby to provide for an increased opening movement of said switch member whereby an increased movement of said operating member is required to move said switch member to a closed circuit position and the temperature of the evaporator for such movement of said switch member to a closed circuit position is increased to a high defrosting temperature effecting defrosting of the evaporator, resilient means in the path of movement of said operating member in moving said switch member to a closed circuit

position normally not engaged by said operating member when said switch member is in said predetermined normal open position but engaged by said operating member during its said increased movement thereby to increase the required pressure by said operating member for operation of said switch member to its closed circuit position, said switch member being free to be moved between said closed and open circuit positions by said temperature responsive means in response to said high defrosting temperature and said normal low temperature to effect defrosting of the evaporator at said high temperature, and a second projection on said knob for engaging said switch member upon rotation of said knob to another predetermined position thereby to hold said switch member in its open circuit position, said cam being arranged to hold said stop in said abnormal position during said continued movement.

6. A control device comprising a switch member, a temperature responsive operating member, a spring forming an operating connection between said members for biasing said switch member from an open to a closed circuit position upon movement of said operating member in response to an increase in temperature, a second spring opposing movement of said operating member, means for varying the force of said second spring,

- 5 a knob provided with a fixed pivot connected to operate said force varying means, a spring latch having at least a portion lying in a plane perpendicular to the pivot of said knob, said portion being provided with a stop projection having a normal position near the pivot of the knob and with an operating projection extending substantially parallel with the pivot of said knob but spaced farther from said pivot than said stop projection, an extension on said switch member engaging said stop projection when said switch member is in its open circuit position and extending substantially parallel with the pivot of said knob toward said knob, a projection on said 10 knob extending parallel with the pivot of said knob for engaging said operating projection upon rotation of said knob in a predetermined direction thereby to move said stop projection to an abnormal position and provide for an increased 15 opening movement of said switch member whereby an increased movement of said operating member is required to move said switch member to a closed circuit position, and a second projection on said knob nearer the pivot of said 20 knob than said first projection thereby to engage said extension upon continued movement of said knob in said predetermined direction and move said switch member to its open position.

JOSEPH W. OWENS.
